UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

HEEL-LIFT ALINING, PRESSING, AND NAILING MACHINE.

Original application filed March 20, 1919. Serial No. 283,693. Divided and this application filed September 15, 1920. Serial No. 410,444.

To all whom it may concern:

Be it known that I, ERASTUS E. WINKLEY, a citizen of the United States, residing at Lynn, in the county of Essex and State of Massachusetts, have invented certain new and useful Improvements in Heel-Lift Alining, Pressing, and Nailing Machines; and I do hereby declare the following to be a full, clear, and exact description of the invention, such as will enable others skilled in the art to which it appertains to make and use the same.

This invention relates to machines for use in the manufacture of shoe heels and more particularly to a machine for alining, pressing, and nailing the component lifts of loosely assembled heels.

One of the general objects of the invention is to provide a machine of the above named character which shall be of relatively compact, durable and inexpensive construction, and which shall uniformly perform its several functions in a rapid, effective and reliable manner.

Another object of the invention is to provide a machine of the character above indicated embodying an improved form for alining and pressing a loosely assembled heel before it is permanently secured together, and which shall function in such manner as to produce tapered heel blanks of substantially regular and perfectly alined lifts, thus insuring a uniformly consolidated and dense heel, free from irregularities and open or checked joints after being subjected to heavy pressure in a heel-compressor. By thus producing substantially perfectly alined heel-piles, it becomes feasible to reduce the size of the component lifts, since the usual liberal allowances for subsequent trimming operations may be materially lessened.

This result is secured through the agency of a feature which comprises an alining and clamping form for tapered heels that is operated in two distinct stages; the first, to close in upon the loosely assembled lifts and aline them while in loose order, in which condition the freshly pasted lifts may be

laterally shifted and perfectly alined with facility, and then to angularly open up slightly to final rigid clamping position to conform to the shape of the heel when the lifts are pressed into intimate engagement in close order, after which the loosely assembled and alined lifts are forced into the form in its final clamping position and subjected to pressure preparatory to being permanently secured together. In preliminarily alining the lifts, the cooperating alining members of the form are brought into predetermined angular positions which correspond to the previously determined angularities or slopes of the heel while its lifts are in loose order. In the open final clamping position, however, the angularities of the members are somewhat greater and are determined in advance to correspond to the slopes of the heel when it shall have been pressed into its final close order formation. Thus, when the loosely alined lifts are pressed into the form in its final clamping position, it is impossible for any of the lifts, and particularly the wedge lifts, to shift laterally or squeeze out of alinement, as is likely to occur in prior art machines of this type which have no provisions for changing the angularity of the form when the heels are subjected to final pressure.

Another object of the invention is to provide, in a heel lift alining, pressing and nailing machine, a form for alining and pressing loosely assembled and freshly pasted heels and clamping them firmly in position while the component lifts are nailed together by an automatically supplied nailing device which is so located as to be entirely free of excess paste that may accumulate in the form during the operation of the machine.

To this end, a feature of the invention resides in the provision of an alining and pressing form comprising a horizontally disposed breast support upon which the loosely assembled heel rests upon its breast, and an automatically supplied nailing device disposed laterally of the form, in a

position free of paste and operating in a horizontal plane to drive a nail through the component lifts. Moreover, the horizontal disposition of the nailing device contributes towards accuracy and uniformity in driving the nails in definite positions with respect to the breasts of the heels, inasmuch as the nails that are automatically supplied to the nailing device always gravitate to a fixed position and, therefore, are driven into the heels in predetermined similar positions, thereby permitting the operator to adjust the angularity of the breast support so as to insure that the nail is located free of that portion of the heel that will later be trimmed off or undercut, as is the case particularly in high women's heels.

A still further object of the invention is to provide in a machine of the above indicated class a semi-automatic power operated alining and pressing form, the initial operation of which is effected manually in such manner as to protect the operator's fingers from injury when the power is applied.

Accordingly, another feature of the invention contemplates the provision of a manually operable controlling handle which actuates the form to partially aline the lifts and which is brought forward by the operator to a position in which it is impossible for the fingers to be in danger before it automatically throws in the clutch to connect the machine to the source of power.

These and other objects of the invention, and the features of construction by means of which they are attained, will become apparent from the following description of the preferred embodiment of the invention illustrated in the accompanying drawings, in which:—

Figure 1 is a view in right side elevation of the lift alining, pressing and nailing mechanism, showing the mechanism in its inoperative open position; Fig. 2 is a phantom perspective view of one of the roll carrying members attached to the main actuating lever; Fig. 3 is a plan view of the lift alining, pressing and nailing mechanism, certain portions being broken away for the sake of clearness, and the mechanism being shown in its inoperative and open position; Fig. 4 is a view in front elevation of the mechanism shown in Figs. 1 and 3, illustrating the mechanism in its closed operating position; Fig. 5 is a sectional view on the line 5—5 of Fig. 4; Fig. 6 is a detail view in front elevation of the end of the nail feeding tube and nail holder; Fig. 7 is a view, partially in side elevation and partially in section, on the line 7—7 of Fig. 3 and showing the parts in their clamping and nailing positions; Fig. 8 is a view similar to Fig. 7, showing certain parts of the heel receiving and holding device adjusted to

act upon a high woman's heel and properly position it for the nailing operation; Fig. 9 is a view, partially in front elevation and partially in section, upon the section line 9—9 of Fig. 7 of the apparatus shown in said figure; Fig. 10 is a view in left side elevation of a portion of a heel receiving and holding device and the alining and clamping form, illustrating the relative positions of the various parts while alining the component lifts in loose order; Fig. 11 is a sectional detail view of a portion of the automatic nail supplying mechanism; Fig. 12 is a view, partially in side elevation and partially in section, on the line 12—12 of Fig. 9 and showing particularly the mechanism for locking the main actuating lever against retraction during the power actuated portion of the cycle of operations; Fig. 13 is a view in side elevation and partially in section of the alining and clamping form, showing the form in its open position; Fig. 14 is an enlarged perspective view of a roll carrying member that is attached to the actuating lever; Fig. 15 is a view in front elevation of a portion of the automatic nail supplying mechanism; Fig. 16 is a similar view in side elevation; Fig. 17 is a plan view of the mechanism shown in Fig. 16; and Fig. 18 is an enlarged detail view in perspective of a portion of the nail supplying mechanism, showing particularly the construction of the nail holding means.

In the drawings the invention is illustrated as embodied in a heel lift alining, pressing and nailing mechanism having the same construction as corresponding mechanism shown and described in applicant's pending application for heel building machines, Serial No. 283,693, filed March 20, 1919, of which the present application is a division.

The illustrative machine comprises, in general, a supporting frame upon which the various parts of the machine are mounted; a heel receiving and holding device, comprising a breast plate 20 and a plurality of relatively movable pressure members 22 and 24, in which loosely assembled heels or heel-piles are placed by the operator; a lift alining form comprising a plurality of alining jaws 26, 28, 30, 32 and 34, for cooperating with the component lifts of the heel to effect their alinement; a pressure applying device including the pressure members 22 and 24, which also constitute parts of the heel receiving and holding device hereinbefore referred to, and which serve to force the preliminarily alined lifts into the alining form and subject them to pressure; a nailing device including a nail driving pin 36 for nailing together the alined and pressed lifts of the heel; and an automatic nail supplying mechanism including a nail holder 38 and a

feed tube 40 for supplying nails to the nailing device.

The mechanism of the present machine is semi-automatic in operation, being under the direct control of the operator, and is adapted to align the loosely assembled lifts of the heel, to subject the heel to pressure, and to clamp it firmly in its final form while its component lifts are being permanently nailed together. The mechanism is of the single cycle type in which the operation is automatically arrested after the completion of each full cycle of operations upon a heel. The mechanism may be adjusted to operate upon heels of various types, but it is particularly adapted to operate upon tapered heels.

The supporting frame of the machine comprises lower side frames 42 and 44 (Fig. 1) and upper frame members 46 and 48 (see also Fig. 3) which are disposed above the side frames 42 and 44 and are secured thereto. The upper side frames 46 and 48 are connected at their forward ends by a front plate 50 and carry upon them a cap plate 52 which constitutes the table of the machine. The cap plate 52 is bolted to the upper frame members 46 and to the front plate 50 and its forward portion 54 (Fig. 7) is relatively narrow and supports the breast plate 20.

The mechanism may be driven from any suitable source of power. As shown in Fig. 1, power is supplied to the mechanism from a sprocket 54 that is mounted upon a power shaft 56 which has a bearing in the lower side frame 44. A chain 58 connects the sprocket 54 with a sprocket 60 that is keyed to a cam shaft 62 which is journaled in the upper frame members 46 and 48 and is continuously driven.

The operation of the machine is controlled through the agency of a clutch which comprises a clutch disk 64 (Figs. 3 and 9) fixed to the cam shaft 62 and having lateral projections or teeth 66. A clutch lever 68 (Figs. 3 and 7) cooperates with the rotating clutch disk 64 and is in the form of a yoke, which is pivotally mounted upon a pin 70, that extends through the hub portion of a cam 72 keyed to a loosely mounted sleeve 74 (Figs. 7 and 9) that extends to the left the entire width of the machine, and which carries a plurality of cams 76, 78 and 80 that are also keyed thereto.

The clutch lever 68 is normally urged into operative position in engagement with one of the clutch disk projections 66 by means of a spring 82, and its disconnection therefrom is effected after each complete revolution thereof, by means of a wedge cam 84 which forms a part of a control arm 86 that is pivotally mounted upon a rod 88 extending between the upper side frames. The operation of the control arm is governed in a manner to be hereinafter described, and

when said control arm is moved into its released position, as shown in Fig. 7, the clutch is thrown into action to connect the normally loose sleeve 74, carrying the several operating cams, to the continuously driven cam shaft 62 whereby the cycle of operation of the mechanism is initiated. After the cycle of operation has been completed, the control arm 86 is moved into its stop position, as shown in Fig. 9, in which the rotating clutch lever 68 is brought into engagement with the wedge cam 84 thereof and is thereby forced out of engagement with the clutch disk projections 66 whereby the clutch is disconnected and the several operating cams 76, 78 and 80 are brought to rest. In order to overcome the inertia of the rotating clutch cam 68 when it is thus disengaged, a spring-pressed pin 90 is provided upon the control arm 86 against which the outer end of the clutch lever 68 is brought to rest.

Having described the supporting frame of the machine and the manner of operating the clutch by means of which power is connected to and disconnected from the several cams 72, 76, 78 and 80, the construction and operation of those parts which are controlled and actuated by said cams will now be set forth.

When a loosely assembled heel-pile is placed by the operator in the heel receiving and holding device of the machine it is positioned with its breast resting upon the horizontally disposed breast plate 20, as shown in Fig. 10. Cooperating with the breast plate 20 are the pressure members 22 and 24 between which the component lifts of the heel are disposed and loosely supported in position. The pressure member 24 is stationarily and removably fixed to a boss 92 (Fig. 7) on the cap plate 52 and projects forwardly to permit its rounded forward end to engage the tread faced end of the heel. The relatively movable pressure member 22 is adjustably mounted by a pivot 94 upon one end of a supporting rod 96 so that it may accommodate itself to the angularity or inclination of the base-left of the heel. The breast plate 20 is removably secured in position so that it may be replaced by other similar breast plates of different thicknesses and inclinations or tapers to properly position heels of varying shapes and forms for the nailing operation. The relatively narrow forward end 54 of the cap plate 52 is provided with a trough 98 which surrounds the breast plate 20 and is intended to collect any excess of paste that may drip, or may be squeezed out from between the component lifts of the heel.

After placing a loosely assembled and freshly pasted heel into the receiving and holding device where it rests upon its breast with its component lifts loosely assembled, or in loose order, as shown in Fig. 10, it is

necessary to laterally shift the lifts while thus loosely arranged to effect their alinement.

This is accomplished by means of the alining form comprising the pivotally mounted alining jaws 26, 28, 30, 32 and 34. Normally the alining jaws of the form occupy their open positions, as illustrated in Figs. 3 and 13, the upper jaw 26 being adapted to be brought into engagement with the upper or rear edges of the lifts, the jaws 28 and 32 being disposed on the left hand side of the heel and adapted to be brought into alining engagement with one side of the component lifts, and the jaws 30 and 34 being disposed on the opposite side of the heel to perform similar functions.

The upper jaw 26 is pivoted upon a pin 100 (Fig. 7) to swing in a vertical plane and said pin is carried at the forward end of a bifurcated arm 102, the rear end of which is pivotally associated with a lug 104 that projects upwardly from the cap plate 52. The bifurcated arm 102 is provided with an upward projection 106 between which and the rear end of the cap plate, a spring 108 is connected, for the purpose of maintaining a roll 110 (Fig. 10), carried on the extended pin 100, in operative position.

The several pairs of side alining jaws 28 and 32, and 30 and 34 are mounted to swing in horizontal planes, each pair of jaws being pivotally mounted upon a vertical pin 112 (Figs. 3 and 13) at the end of a horizontally disposed swinging supporting arm 114, said supporting arm being pivoted upon a stud 116 and being biased to its outermost position by means of a spring 118 that is attached between it and a point on the cap plate 52. The lower jaws 28 and 30 are also provided with outwardly extending arms 120 to the ends of which are attached springs 122 which serve to yieldingly urge them into their inward alining positions. The upper alining jaws 32 and 34, however, are merely pivoted upon the pins 112 and are free to occupy any position they may assume.

The several jaws 26 to 34, inclusive, of the alining form are adapted to be actuated through the agency of a manually operable actuating lever 124 which assumes the position illustrated in Figs. 3 and 13 when the alining jaws are open. The actuating lever 124 (Figs. 3, 4, 5 and 7) is yoke shaped in form, having a plurality of arms 126, the lower ends of which are pivotally mounted upon a shaft 128 extending between the respective upper side frames, and the upper end of the lever is provided with a handle 130 by means of which it may be actuated. Between the relatively adjacent upper portions of the side arms 126 of the actuating lever 124, a member 132 (Figs.

5 and 14) carrying a roll 134, is mounted for vertical adjustment by means of a plurality of bolts 136, while an adjusting screw 138 is provided through the upper end of the actuating lever 124 which projects downwardly into engagement with the upper surface of the roll carrying member 132. By loosening the bolts 136 and adjusting the screw 138 in or out, the position of the member 132 and roll 134 may be varied as desired. The function of this roll is to engage a cam surface 140 (Fig. 7) provided upon the upper alining jaw 26, and in conjunction with the engagement of a tail-piece 142 of the member 132 with the roll 110 carried upon the pin 100, to actuate the upper alining jaw 26 into its preliminary alining and subsequent final clamping positions when the actuating lever 124 is manually brought forward by the operator. A spring 144 interposed between the free end of the alining jaw 26 and the lever 124 serves to bias said jaw to its open position.

The several pairs of side alining jaws 28 and 32, and 30 and 34 are also actuated by the forward movement of the actuating lever 124. For this purpose, each arm 126 of the actuating lever 124 is provided with an adjustably positioned member 146 (Figs. 2, 4 and 13) which carries a roll 148 upon a pin 150 that extends downwardly from said member a material distance. Each of the roll carrying members 146 is provided with a laterally extending arm 152 having an angularly disposed slotted end 154, the arm 152 being also provided with a slot 156 (Fig. 2). The arm 152 is seated in a notch 158 in the side arm 126 of the actuating lever and is secured thereto by means of a bolt 160 (Fig. 13) which projects through the slot 156 and into the rear edge of the side arm 126. For purposes of lateral adjustment of the roll 148 and the pin 150, an adjusting bolt 162 is provided which projects through the slotted end 154 of the arm 152 and is threaded into a boss 164 that projects laterally from the side arm 126.

When the manually operable actuating lever 124 occupies its released position, as shown in Figs. 1, 3 and 13, the downwardly extending ends of the pins 150 engage the arms 120 of the lower alining jaws 28 and 30 and hold said jaws in their open positions against the action of the springs 122.

As the actuating lever 124 is brought forward by the operator, the advance movement of the pins 150 permits the springs 122 to progressively swing the lower alining jaws 28 and 30 into engagement with the lateral edges of the component lifts of the loosely assembled heel that rests in the receiving and holding device. The lower jaws, therefore, tend to yieldingly aline the lifts.

As the actuating lever 124 moves forward, the several rolls 148 that are mounted upon the pins 150 are brought into engagement with cam surfaces 165 formed on the rear edges of the upper alining jaws 32 and 34, whereby said jaws are positively moved into their alining positions in engagement with the lateral edges of the loosely assembled lifts to effect their alinement.

Concurrently with this alining operation of the side alining jaws, the forward movement of the actuating lever 124 also actuates the upper alining jaw 26 into alining position by reason of the engagement of the roll 134 with the cam surface 140 of said jaw in conjunction with the cooperation of the tail-piece 142 with the roll 110. The upper alining jaw 26, therefore, is forced downwardly into engagement with the upper or rear ends of the loosely assembled lifts to force their breast edges firmly against the breast plate 20.

An important feature of the invention resides in the peculiar operation of the alining jaws constituting the alining form, which are actuated in two stages or steps, in the first of which the upper jaw 26 and two upper side jaws 32 and 34 are brought into predetermined alining positions, the angularity or inclination of which corresponds substantially to the slope or inclination of the engaged portions of the heel while the component lifts thereof are loosely assembled, or in loose order. The desired angular positions of the jaws in their preliminary alining positions is secured by the use of jaws having properly designed cam surfaces and by adjustment in the positions of the operating rolls 134 and 148, the jaws being replaced by other suitable ones to secure the requisite angularity, and the positions of the rolls being suitably adjusted to accommodate heels of different sizes but of similar slopes or tapers.

In the second stage of operation of the alining form, the several jaws thereof are permitted to be opened up slightly to a predetermined greater inclination or angularity which conforms to the slope or inclination of the heel after the lifts have been forced into the form and subjected to pressure to bring them into intimate contact, or into close order, it being evident that the slope of a heel of closely assembled lifts is greater in angularity than that of the same heel while the lifts are loosely assembled. This change in the positions of the alining jaws, however, is not effected until the heel is subjected to pressure, which is effected in the following manner.

Assuming the lifts to be preliminarily alined in their loose order, as indicated in Fig. 10, the pressure member 22 is actuated to apply pressure thereto and clamp the lifts

against the stationary pressure member 24. As already stated, the pressure member 22 is pivotally mounted upon the rod 96 so that it may accommodate itself to any pitch of heel. This rod 96 projects through an upwardly extending portion 168 (Fig. 7) of a plunger 170, and is secured thereto by suitable nuts 172. The plunger 170 is slidably mounted for back and forth motion in an opening provided in an enlarged portion 174 (Fig. 9) of the cap plate 52, and said plunger projects to the rear beyond said enlarged portion and carries a plurality of rolls 176 and 178 (Fig. 7). The forward end of the plunger 170 is provided with a recess to receive a coiled spring 180 which is seated against the bottom of the recess and against an upwardly projecting arm 182 that forms a part of the front plate 50. The spring 180 is relatively strong and normally urges the plunger 170, together with the movable pressure member 22, rearwardly to cause said pressure member to force the preliminarily alined lifts into the form composed of the several alining jaws and to subject the heel to a predetermined yielding pressure, irrespective of its height.

Prior to the application of pressure to the heel, the pressure member 22 is maintained in its open and inoperative position against the action of the spring 180 by means of a bell crank 184 that is pivotally mounted upon a stud 186 carried by the side frames 46 and 48 and which acts upon the rear end of the plunger 170. The other arm of said bell crank carries a roll 188 that is adapted to cooperatively engage the cam 76. This cam is designed to permit the pressure applying spring 180 to actuate the pressure member 22 at the proper time, and to subsequently release said pressure member by causing the bell crank 184 to act upon the end of the plunger 170.

As the preliminarily alined heel is yieldingly forced into the form in the manner just described, the operating rolls 134 and 148 that cooperate with the respective cam surfaces 140 and 164 of the alining jaws 26, 32 and 34, pass over the points 190 and 192 of the respective cam surfaces, thereby permitting said jaws to open up to predetermined increased angularities or inclinations which as hereinbefore stated, correspond to the exact pitch of the heel after it has been subjected to pressure. The alining jaws 26, 32 and 34 are thus firmly held in their final alining and clamping positions, as shown in Figs. 4 and 7, to constitute a rigid form into which the preliminarily alined lifts are forced and subjected to pressure.

Although the lower alining jaws 28 and 30 are at first yieldingly actuated into their preliminarily alining positions by the springs 122, the forward movement of the manually operable actuating lever 124 brings

the extended lower ends of the pins 150 into positions spaced slightly behind said jaws. Said pins, therefore, serve as rigid restraints or stops for the jaws when the jaws are spread outwardly as the loosely assembled and preliminarily alined lifts are subjected to pressure. Thus, all of the alining jaws of the form are rigidly held in their final alining and clamping positions which are determined in advance to be such as to exactly conform to the heel after it has been subjected to pressure. It is clear, therefore, that by reason of the two stage alining operation no disarrangements of the component lifts of the heel are possible and that a substantially perfectly alined heel is insured.

Although the initial forward movement of the actuating lever 124 is effected manually, the latter part of the operation is produced by the application of power. Moreover, this application of power to the actuating lever is not permitted until the several jaws of the alining form have been manually moved into substantially their preliminary alining positions, after which it is impossible for the operator's fingers to remain in the machine where they may be injured. Furthermore, having once brought the actuating lever 124 forward to a position in which power is applied thereto, means is provided for preventing the manual retraction thereof by the operator.

To effect these results, the actuating lever 124 is connected to the upper end of the clutch control arm 86 by means of a link 194 (Figs. 1 and 7). When the actuating lever occupies its inoperative position, as shown in Figs. 1 and 9, the control arm 86 is maintained in such position as to prevent the clutch lever 68 from being thrown into engagement with the clutch disk 64, whereby the application of power is prevented. When, however, the actuating lever has been manually brought forward to an extent sufficient to place the jaws of the alining form in substantially their preliminary alining positions, the control arm 86 is withdrawn and the clutch lever 68 released and permitted to effect an operative driving engagement with the continuously operating clutch disk 64 whereby all of the cams 72, 76, 78 and 80 are connected to the source of power.

Just prior to the throwing in of the clutch to effect the power operation of the machine, a roll 196 (Figs. 3 and 12) that is carried at the end of a lever 198 is dropped in a cam path 200 in the cam 80, as indicated in dot and dash lines in Fig. 12. The lever 198 is pivotally mounted upon a stud 202 projecting inwardly from the left hand side of the cap plate 52, and its other end is connected by means of a link 204, having bifurcated ends, with an arm 206 forming an integral part of the manually operable ac-

tuating lever 124. The cam 80 is provided with a spring-pressed latch 208 adjacent the opening through which the roll 196 is dropped into the cam path 200, so that as soon as the roll has passed the yielding 70 latch 208, it serves as a lock to prevent the removal of the roll therefrom, and at the same time to restrain the actuating lever 124 against manual retraction.

Having thus locked the manually operable 75 actuating lever 124 in the manner just described, and having connected the machine to the source of power, the several cams are started into operation. Immediately thereafter the cam 80 operates upon the roll 196 so to force the actuating lever 124 to its foremost position and to release the several alining jaws from their preliminary alining positions. Subsequently the cam 76 (Fig. 7) releases the pressure-applying spring 180 85 and the pressure member 22 is actuated to force the heel into the alining jaws in their final alining and clamping positions and to subject the heel to a predetermined yielding pressure.

An additional and positive pressure is then applied to the heel in the form, after which the pressure member 22 is positively restrained to provide a rigid and firm backing against which the nailing mechanism may operate. To this end, an eccentric wedge cam 212 (Fig. 7) is rotatably mounted upon a stud 214 and is acted upon by a spring 216 that is attached through an adjustable tension device 218 to the upper end of a supporting arm 220 which projects upwardly from the cap plate 52. An arm 222 forms a part of a bell crank with the wedge cam 212, and carries at its end a roll 224 that is adapted to cooperate with the cam 72 on 100 the cam shaft 62. The wedge cam 212 in its operative position, as shown in Fig. 7, cooperatively engages the roll 176 that is fixed to the side of the plunger 170 to which the pressure member 22 is attached. The spring 110 216 is preferably heavy relative to the pressure-applying spring 180, and the tension thereof is adjustable by means of the tensioning device 218.

The cam 72 is designed and angularly positioned upon the cam shaft so that after a predetermined yielding pressure has been exerted upon the heel through the spring 180, the roll 224 on the wedge cam bell crank is disengaged from the cam 72, thereby permitting the relatively heavy spring 216 to pull the wedge cam 212 upwardly against the roll 176. By reason of the strength of the spring and the eccentric form of the wedge cam, said cam is caused to force the plunger 170, together with the pressure member 22, toward the right to exert an additional and positive pressure upon the heel. The amount of positive pressure to which the heel is thus subjected depends 130

entirely upon the strength of the spring 216 and, therefore, any degree of pressure may be obtained in accordance with the adjustments of the spring tensioning device 218.

5 With this construction it is clear that the heel, regardless of its height, is first subjected to a predetermined and substantially uniform yielding pressure that is effected by the spring 180, and thereafter, the heel is 10 subjected to an additional predetermined amount of positive pressure through the action of the wedge cam 212. The wedge cam 212 serves a double function, since it also positively locks the pressure member 22 15 in its final pressure-applying position so that it is positively held and constitutes a rigid backing against which the nail is driven in a manner to be later described.

The next operation is to nail together the 20 alined and pressed heel, and this is accomplished by the nailing device comprising the nail driver 36 (Figs. 6 and 7). The nail driver 36 is horizontally disposed and projects slidably through an opening in the 25 rear pressure member 24 which is provided with a V shaped groove 226, to which the nails are automatically supplied by the feed tube 40 and in which the nails lie in substantially horizontal position. The nail 30 driver 36 is held by a suitable chuck 228 that is mounted upon the end of a plunger 230 that is adapted to reciprocate in an opening in a longitudinal boss 232 that forms an integral part of the cap plate 52. 35 The rear end of the plunger 230 is provided with an adjustable end member 234 (Figs. 3 and 7) having a vertically disposed channel or groove to receive an engaging member 236 that is secured at the upper end of 40 a bell crank 238. The end member 234 is also provided with a socket 240 to receive one end of a spring 242 that is held in a recess 244 in the boss 232 (Figs. 7 and 9). The spring 242, therefore, serves to urge the 45 nail driver 36 rearwardly and to maintain it in its retracted inoperative position and, at the same time, to hold a roll 246 (Fig. 7) carried at the other end of the bell crank 238 in engagement with the cam 78 on the 50 cam shaft 62. The cam 78 controls the operation of the nail driver 36 and is designed to positively advance the nail driver 36 to drive a nail through the component lifts of the heel after the heel has been subjected to 55 pressure and firmly clamped in position. The nail is driven through the heel in the direction of its height and against the rigid backing provided by the positively locked pressure member 22 which serves to turn 60 over or clench the point of the nail when it is engaged thereby, as shown in Fig. 7.

Among the important features of the invention is the construction and arrangement of the nail driving device with respect to 65 the means for holding and clamping the

freshly pasted heel in position to be nailed. This arrangement is such that the freshly pasted heel is placed on its breast upon the breast plate 20 and the nail driver is located adjacent and to the rear thereof and operates in a horizontal plane during its nailing operation. Thus, the heel receiving and holding means and the nail driving device are disposed side by side so that any excess of paste that may be carried by the freshly pasted heel or may be squeezed out from between its lifts, cannot possibly come in contact with the nailing apparatus, which always remains clean and free from paste and operates with reliability and effectiveness. Moreover, this arrangement also permits of the use of an automatic nail supplying mechanism which it is impossible to employ, in a position in which it may be gummed by contact with paste.

Before describing the construction and operation of the automatic nail supplying mechanism, however, another advantageous feature of this horizontal side by side arrangement should be considered. With this arrangement, the nail receiving groove 226 is horizontally disposed and, therefore, as the nails are supplied thereto prior to the nail driving operations, said nails gravitate to and always occupy similar positions resting at one end upon their heads and at the other upon their pointed ends. This position is substantially horizontal, although slightly inclined thereto by reason of the somewhat enlarged diameter of the head of the nail. Each nail, however, occupies the same position and, therefore, must be driven into the heel in substantially definite and fixed position, it being well known in the art that nails are driven along lines in the direction in which they are positioned when the driving operation takes place.

Advantage is taken of this fact, in order to insure the proper positioning of the securing nails in the heels, and particularly in relatively high heel-piles from which high Louis heels are to be made. In some forms of Louis heels the breasts of which are to be greatly under cut and which slope forwardly at quite extreme angles, the areas of cross sections of the heels at certain points are extremely small, which makes it necessary to carefully locate the nails which secure together the component lifts so that they shall not protrude beyond the limits of the heels in their final forms.

To adapt the alining, pressing and nailing mechanism of the present invention to operate upon heels of different styles and forms and to properly position the securing nails therein in accordance with the peculiar characteristics of the heel being operated upon, the heel receiving and holding device comprising the breast plate 20 and the relatively movable pressure members 22 and 24

are made adjustable. Fig. 8 illustrates said receiving and holding device adjusted to properly position and hold a heel-pile from which a high Louis heel is to be produced, the final shape of the heel being indicated in dotted lines. In this construction, the breast plate 20 is tapering and inclined in form; the adjustable pressure member 22 is tilted upon its pivot to accommodate the inclination 10 of the base-lift of the heel; while the rounded end of the stationary pressure member 24 permits the heel to be properly positioned with respect thereto. The taper and thickness of the breast plate 20 is suitably 15 chosen with respect to the particular characteristics of the heel to be built in order to properly position it so that the nail, which is always driven in a predetermined direction dependent upon its definite position in 20 the nail receiving groove 226, is driven through the restricted area of the heel and in such position that it will not be exposed when the heel breast is under cut and the lateral surface trimmed to its final shape.

25 Referring again to Fig. 7 after the nail has been driven by the nail driver 36, the cam 80 (Figs. 3 and 12) operates through its cam surface 248 to force the cam roll 196 outwardly and, through the connections already described, to positively throw back the actuating lever 124 of the alining form into its normal retracted position, as shown in Figs. 1, 12 and 13. This operation releases the several alining and clamping jaws 30 to 34, inclusive, as will be understood.

35 At substantially the same time, the cam 72 (Figs. 3 and 7) is brought into position to engage the roll 224 whereby the wedge cam 212 is withdrawn from its operative 40 position to release the plunger 170 carrying the pressure member 22. Subsequently, the cam 76 operates upon the roll 188 to cause the bell crank lever 184 to force the plunger 170 and its pressure member 22 forwardly 45 against the action of the spring 180 whereby the pressure is relieved from the heel and the heel receiving and holding device is restored to its initial open position.

Immediately after the pressure member 50 22 has been retracted to its open position, the cam 78, by reason of a raised portion 250 (Fig. 7) thereof, cooperates with the roll 246 and bell crank 238 to give the nail driver 36 a slight projection forwardly to loosen 55 the heel that may possibly have adhered to the breast plate 20. The nail driver is then immediately retracted to its initial position, at which time the alining, pressing and nail-ing mechanism is brought to rest by automatically disengaging the clutch lever 68 60 from the continuously rotating clutch disk 64. This is accomplished through the agency of the wedge cam 84 on the control arm 86 which has, in the meantime, been placed in 65 its operative stop position by the automatic

retraction of the main actuating lever 124, in which position it engages and throws out the rotating clutch arm 68 when it reaches a position in which the engagement may take place, as shown in Fig. 9.

70 As already stated, the horizontal and side by side relation of the heel receiving and holding device and the nail driving device permits the employment of an automatic nail supplying mechanism. This mechanism 75 is adapted to supply a nail to the nail receiving groove 226 at each cycle of operation of the machine. The nail supplying mechanism comprises the nail holder 38 and the feed tube 40 which delivers the nails to the receiving groove 226, and said nail holder 38 is conveniently mounted above the machine upon a bracket 252 (Figs. 1, 15, 16 and 17) which is secured to the cap plate 52. The upper portion of the bracket 252 carries a fixed pin 254 that projects upwardly therefrom to receive a rotatable supporting spider 256 that is yieldingly held in position upon a portion of the bracket 252 and which is provided with a plurality of radial arms 258 that are joined by means of segmental members 260. At the extremities of the arms 258, a plurality of upwardly projecting pins 262 are located, and these pins 262 are adapted to support the nail holder 38 which comprises an annular member 264 having a plurality of inwardly extending apertured lugs 266 which set over the pins 262 and by means of which the annular member 264 is removably supported in position. The nails are held in both the inner and the outer corrugations of a corrugated strip of sheet material 268 that is secured to the periphery of the annular member 264, and in order to retain the nails in the outer corrugations of said strip, a plurality of bands 270 are positioned around the periphery of the corrugated strip and in contact therewith. To support the nails, a supporting ring or plate 272 is disposed immediately beneath the annular member 264 and is loosely supported in position by means of washers 274 (Fig. 11) that are held upon screws 276 which are threaded into inwardly projecting lugs 278 that are formed integrally with the annular member 264.

80 This structure is such that the annular member 264 may be removed from the pins 262 and, through the agency of the supporting washers 274, carries the supporting ring 272 with it. The supporting ring 272 is provided with an aperture 280 that is located beneath the corrugations of the nail holder in such position that as the holder is advanced in steps, the nails contained therein are progressively brought over the aperture 280 whereby said nails are permitted to drop through and into the flexible feed tube 40 which is supported by the bracket 85 90 95 100 105 110 115 120 125 130

252 in a position directly beneath said aperture. During the normal operation of the nail supplying mechanism, the supporting ring 272 is restrained against rotative movement by means of a fixed pin 282 (Fig. 11) that projects into an opening in said ring when it is properly positioned.

The nail holder 38 is adapted to be advanced, one step at a time, at each cycle of operation of the alining, pressing and nailing mechanism, and its feeding movement is effected by means of a spring-pressed pawl 284 that is pivotally mounted upon a pin 286 at the upper end of an arm 288 which forms a part of a bell crank pivotally mounted upon the bracket 252 by means of a pin 290. The bell crank also comprises an arm 292 that carries at its outer end a roll 294 which cooperatively engages a cam path 296 that is provided in a cam 298. The cam 298 is fixed to a shaft 300 journaled in the bracket that carries a sprocket 302 which is connected by means of a chain 304 (Fig. 1) to a sprocket 306 (Fig. 9) that is fixed by means of a set screw 307 to the sleeve 74 surrounding the cam shaft 62 and upon which the several operating cams of the machine are mounted.

Inasmuch as the nail holder 38 is advanced in steps by reason of the engagement of the pawl 284 with each outer corrugation of the corrugated member 268, and inasmuch as nails are contained in both the outer as well as the inner corrugations of said member, it is necessary to make provision for advancing the nail holder, a half corrugation at each step. To effect this result, the ratio of the sprockets 302 and 306 is so chosen that for each complete cycle of the machine, the cam 298 is rotated a half revolution, which by reason of its design, causes the pawl 284 to advance the nail holder 38 a step corresponding to one half of a corrugation. During the next succeeding cycle of operation of the alining, pressing and nailing mechanism, the cam 298 completes the other half of its revolution during which it advances the nail holder 38 another half corrugation. The pawl is then retracted to engage the next succeeding corrugation. In this manner, the nail holder 38 is advanced in steps, a half corrugation at a time for each cycle of operations of the alining, pressing and nailing mechanism, whereby the nails contained in the inner and outer corrugations of the corrugated strip 268 are progressively positioned over the aperture 280 and feed tube 40 and are supplied one at a time through the tube 40 to the nail receiving groove 226 in position to be acted upon by the nail driver 36.

When the nail holder 38 has been emptied, the annular member 264, together with the supporting ring 272, may be removed bodily for reloading. To facilitate the removal of

the nail holder, a manually operated detent or latch 308 is provided which is pivoted upon a pin 310 and may be swung into position to engage the pawl 284 and positively hold it in inoperative position to permit the nail holder 38 to be raised from the supporting pins 262 and removed. To prevent relative rotative movement between the annular member 264 and the supporting ring 272 carried thereby upon the washers 274, said annular member 264 is provided with a spring-pressed pin 312 (Fig. 11) that, when the holder is removed, is adapted to be projected into the opening in the ring 272 that receives the fixed pin 282 when the holder is in position. This construction insures that no nails are lost through the feeding aperture 280 after the nail holder has been loaded.

When the nail holder 38 is again placed in operative position, upon the pins 262, the pin 282 projects into the opening in the supporting ring 272 and by reason thereof, pushes out the spring-pressed pin 312, whereby the supporting ring 272 is held stationary in position, while the annular member 264 resting upon the spider 256 is permitted to be stepped along in the manner already described to successively deliver the nails into the feed tube 40.

While the invention has been illustrated and described as embodying a more or less specific construction, arrangement and location of parts, it will be understood that the invention is not so restricted and that many of the advantages and benefits of the invention may be derived from a machine that varies materially from that set forth. The preferred embodiment herein shown and described is therefore merely illustrative of the invention and inasmuch as many modifications may be made therein without departing from the spirit and scope of the invention, only such limitations should be imposed as are indicated in the appended claims.

Having described the construction and operation of the preferred form of the present invention that which is claimed as new, is—

1. A heel machine having, in combination, a form for receiving a heel of loosely assembled lifts, means for actuating the form in two stages to first preliminarily aline the component lifts and then to cause the form to occupy its final alining and clamping position, and means for subsequently forcing the heel in the direction of its height into the form and to subject it to pressure.

2. A heel machine having, in combination, a form for receiving a heel of loosely assembled lifts, means for actuating the form in two stages to first close the form to preliminarily aline the component lifts, and then

to partially open the form to its final alining and clamping position, and means for forcing the component lifts into intimate engagement and into the form to clamp the heel under relatively heavy pressure.

3. A heel machine having, in combination, a form for receiving a heel of loosely assembled lifts, means for closing the form to aline the loosely assembled lifts and subsequently releasing the lifts and partially opening the form to clamping position, and means for thereafter forcing the heel into the form and clamping it under relatively heavy pressure.

4. A heel machine having, in combination, relatively movable means for engaging the opposite ends of a heel of loosely assembled lifts, an adjustable form for engaging the edges of the lifts, means for closing the form to aline the loosely assembled lifts and subsequently partially opening the form to final position, and means for effecting relative movement between said end engaging members to subject the heel to pressure.

5. A heel machine having, in combination, means for supporting upon its breast a heel of loosely assembled lifts, relatively movable members for engaging the respective ends of the heel, means movable towards the sides and rear of the heel so positioned for alining the component lifts thereof, and means for effecting relative movement between said end members to clamp the heel under pressure.

6. A heel machine having, in combination, means for receiving a heel of loosely assembled lifts, comprising a breast supporting member and a plurality of movable end members, means for alining the component lifts and forcing their breast edges into engagement with said supporting member, means for subsequently adjusting said alining means to final clamping position, and means for actuating one of the end members to force the loosely assembled and alined heel into clamping position and to subject the heel to pressure.

7. A heel machine having, in combination, a form for receiving a heel of loosely assembled lifts comprising a plurality of movable jaws for cooperating with said heel, means for closing the jaws upon the heel to aline its component lifts and subsequently partially opening said jaws into clamping position, and means for forcing the loosely assembled and alined lifts into the jaws in their clamping position and into engagement one with the other.

8. A heel machine having, in combination, a form for receiving a heel of loosely assembled lifts comprising a plurality of pivoted jaws for engaging the edges thereof, means for closing the jaws upon the heel to aline the component lifts and for subsequently partially opening said jaws, and

means for forcing the heel into said partially opened jaws and applying pressure thereto.

9. A heel machine having, in combination, 70 a form for receiving a heel of loosely assembled lifts comprising a breast supporting member, a plurality of relatively movable end members and a plurality of pivotally mounted jaws for engaging the edges of the lifts, said jaws being provided with cam surfaces, means engaging the cam surfaces of said jaws for first closing the jaws to aline the lifts and then for partially opening the jaws to final clamping position, and means for actuating one of said end members to force the alined heel under pressure into said jaws.

10. A heel machine having, in combination, 85 means for receiving a heel of loosely assembled lifts comprising a breast supporting member, a plurality of end members, a pivotally mounted jaw for engaging the rear ends of the lifts and a plurality of pivotally mounted jaws disposed on each side of the heel for engaging the edges of the lifts, means for closing said jaws to aline the lifts and for partially opening and rigidly restraining said jaws in final clamping position, and means for actuating one of 95 said end members to force the heel under pressure into said restrained jaws.

11. A heel machine having, in combination, 100 means for receiving and holding a heel of loosely assembled lifts, normally restrained spring actuated means for engaging the edges thereof, other means for engaging said edges, and means for releasing said normally restrained spring actuated means to permit said means to yieldingly engage and aline said lifts and for positively 105 actuating said other means to cause them to engage and aline said lifts.

12. A heel machine having, in combination, 110 means for receiving and holding a heel of loosely assembled lifts, normally restrained spring actuated means for engaging the edges thereof, other means for engaging said edges, means for releasing said spring actuated means to permit said means to 115 yieldingly engage and aline said lifts and for positively actuating said other means to engage and aline said lifts, means for providing a rigid restraint behind said spring actuated means and for partially retracting and rigidly restraining said other alining means, and means for forcing the alined and loosely assembled lifts into said restrained alining means and subjecting them to pressure.

13. A heel machine having, in combination, 125 means for receiving and holding a heel of loosely assembled lifts, a plurality of clamping jaws for engaging the edges thereof, certain of said jaws being normally restrained and yieldingly actuated into en- 130

gagement with the lifts for effecting their alinement, and additional means for independently actuating the other jaws into alining engagement with said lifts.

14. A heel machine having, in combination, means for receiving and holding a heel of loosely assembled lifts, a plurality of clamping jaws for engaging the edges thereof, certain of said jaws being normally restrained and yieldingly actuated into alining engagement therewith, cam surfaces associated with the other jaws, means for releasing said spring actuated jaws and for cooperating with said cam surfaces to positively actuate the other jaws into alining engagement with the lifts and for subsequently partially retracting said jaws into rigid clamping position, means for forcing said lifts into said jaws in their clamping position, and means spaced behind said spring actuated jaws for providing a rigid restraint therefor as the lifts are forced into their clamping position.

15. A heel machine having, in combination, a form for receiving a heel of loosely assembled lifts, means for actuating the form in two stages to first preliminarily aline the component lifts and then to cause the form to occupy its final alining and clamping position, means for subsequently forcing the heel in the direction of its height into the form and subjecting it to pressure, and means for nailing together said lifts.

16. A heel machine having, in combination, a form for receiving a heel of loosely assembled lifts, means for closing the form to aline the loosely assembled component lifts and subsequently releasing the lifts and partially opening the form to clamping position, means for thereafter forcing the heel into the form and clamping it under relatively heavy pressure, and means for nailing the lifts together while so clamped.

17. A heel machine having, in combination, means for receiving and holding a heel of loosely assembled lifts, two pairs of clamping jaws for engaging the opposite edges thereof, one pair being normally restrained and yieldingly actuated into engagement with the lifts for effecting their alinement, and means for concurrently actuating the other pair of jaws into alining engagement with said lifts by a movement relative to the movement of the first named pair of jaws.

18. A heel machine having, in combination, means for receiving and holding a heel, and a single means acting in the direction of the height of the heel for subjecting it to a predetermined degree of pressure in a plurality of immediately successive and distinct steps.

19. A heel machine having, in combination, means for receiving and holding a heel, and means acting in the direction of the

height of the heel for subjecting it to a predetermined yielding pressure irrespective of its height, and means for subsequently exerting an additional predetermined positive pressure thereon.

20. A heel machine having, in combination, means for receiving and holding heels of varying height, and means acting in the direction of the height of the heel for subjecting the heel whatever its height successively to a yielding pressure and a predetermined positive pressure.

21. A heel machine having, in combination, means for receiving and holding a heel, and means acting in the direction of the height of the heel for subjecting it to a predetermined yielding pressure, means for exerting an increased positive pressure thereon, and means for adjusting said positive pressure means to vary the pressure exerted thereby.

22. A heel machine having, in combination, means for receiving and holding a heel, means acting in the direction of the height of the heel for applying a yielding pressure thereto, means for positively locking said yielding pressure means in its final pressure-applying position, and means for driving a nail through said heel and against the locked pressure means.

23. A heel machine having, in combination, means for receiving and holding a heel, means acting in the direction of the height of the heel for applying a yielding pressure thereto, means for subsequently applying an increased positive pressure thereto and providing a rigid restraint therefor, and means for driving a nail through said pressed and rigidly restrained heel.

24. A heel machine having, in combination, means for receiving and holding a heel, means acting in the direction of the height of the heel for applying a predetermined yielding pressure thereto irrespective of its height, and means for positively locking said yielding pressure means in its final pressure-applying position.

25. A heel machine having, in combination, means for receiving and holding a heel of loosely assembled lifts, comprising a supporting plate upon which the lifts rest, a stationary member for engaging one end of the heel and a spring actuated pressure member for engaging the other end of the heel and subjecting the heel to a predetermined pressure irrespective of its height, means for positively locking the pressure member in operative position, and means associated with the stationary end member for driving a nail through the heel in a direction towards the locked pressure member.

26. A heel machine having, in combination, a form for receiving and holding a heel of loosely assembled lifts, means for causing said form to aline said lifts, yield-

ingly operated means for forcing said lifts into the form and subjecting them to pressure, means for rigidly restraining said pressure means in operative position, and 5 means for driving a nail through said lifts in a direction toward said rigidly restrained pressure means.

27. A heel machine having, in combination, a form for receiving and holding a 10 heel of loosely assembled lifts, means for alining and clamping said lifts, means acting in the direction of the height of the heel for applying a predetermined yielding pressure to said heel, means for rigidly restraining said pressure-applying means in its 15 operative position, and means for driving a nail through said heel while under pressure and against said restrained pressure-applying means.

28. A heel machine having, in combination, means for receiving and holding a pile 20 of loosely assembled lifts comprising a breast support and cooperating end pressure members, means for alining said lifts, 25 normally restrained spring actuated means for causing one of said pressure members to apply pressure to the heel, means for releasing said normally restrained spring actuated pressure means, means for locking said pressure means in its operative position, and 30 means for driving a nail through the component lifts of the heel and against said locked pressure-applying member.

29. A heel alining and nailing machine 35 having, in combination, means for holding a heel of freshly pasted lifts resting upon its breast, a horizontally disposed nailing device located at one side of said holding means for driving a nail through the lifts 40 of the heel held thereby, and automatic means for supplying nails to said nailing device.

30. A heel alining and nailing machine 45 having, in combination, means for holding a heel of freshly pasted lifts resting upon its breast and including means operative after the heel is positioned for alining the lifts thereof, a horizontally movable nail driving device disposed adjacent one end of 50 the heel in a position free of paste, and means for automatically supplying nails to said nail driving means.

31. A heel alining and nailing machine 55 having, in combination, means for holding a heel of loosely assembled and freshly pasted lifts resting upon its breast, comprising a breast supporting member, a plurality of end engaging pressure members and cooperating members movable into engagement 60 with the heel for alining its component lifts, a horizontally movable nail driving means disposed laterally of said holding means in a position free of paste for nailing together the component heel lifts, and means also 65 located in a position free of paste for auto-

matically supplying nails to said nail driving means.

32. A heel alining and nailing machine having, in combination, means for holding a heel of loosely assembled and freshly pasted 70 heels resting upon its breast, comprising a breast supporting member, a plurality of end engaging pressure members, a plurality of lift alining members and means for actuating said alining members into lift-alining position and subsequently actuating said pressure members to subject the heel to pressure, means disposed at the side of said holding means in a position free of paste for 75 nailing together the alined and pressed heel lifts, means for supplying nails to said nailing means, and means dependent upon the operation of said actuating means for effecting the automatic operation of said nailing means and said nail supplying means. 80

33. A heel machine having, in combination, means for receiving and holding a heel of pasted lifts comprising a supporting member upon which the lifts rest, means 90 associated with said member for clamping together the lifts under pressure, an automatic nailing device for driving a nail through said lifts, means for releasing said clamping means, and means associated with said nailing device for causing it to loosen 95 any nailed heel that may have adhered to said supporting member.

34. A heel machine having, in combination, means for alining a heel of loosely assembled lifts, means for subjecting said heel to pressure, a nailing device for nailing together the alined lifts of the heel while under pressure, manually operable means for actuating said alining means, and means controlled by said manually operable means and operative only when said alining means is substantially in alining position for automatically actuating said pressure means and said nailing device. 100

35. A heel machine having, in combination, means for alining a heel of loosely assembled lifts, means for subjecting said heel to pressure, a nailing device for nailing together the alined lifts of the heel while under pressure, manually operable means for actuating said alining means, and means controlled by said manually operable means and operative only when said alining means is substantially in alining position for automatically actuating said pressure means and said nailing device and subsequently retracting said pressure applying means, said manually operable means, said nailing device and said alining means. 110

36. A heel machine having, in combination, means for alining a heel of loosely assembled lifts, means for subjecting said heel to pressure, a nailing device for nailing together the alined lifts of the heel while under pressure, manually operable 120

means for actuating said alining means, and means controlled by said manually operable means just prior to reaching its alining position for locking said manually operable means against subsequent manual release, for actuating said pressure means and said nailing device, and for subsequently releasing and restoring said manual operable means, said pressure means and said nailing device to their normal positions.

37. A heel machine having, in combination, means for receiving and holding a heel of loosely assembled lifts, means for alining said lifts, manually operable means for actuating said means into substantially alining position, and means controlled by the operation of said manually operable means just prior to reaching its alining position for locking said means against retraction and for automatically actuating said means to final position.

38. A heel alining and nailing machine having, in combination, means for receiving a heel of loosely assembled lifts, manually operable means for alining said lifts, and

means dependent upon the operation of said alining means for applying pressure to the lifts, nailing together the lifts, and supplying nails for the nailing operation.

39. A heel alining and nailing machine having, in combination, means for receiving a heel of loosely assembled lifts, manually operable means for alining said lifts, means for applying pressure to the lifts, means for nailing the lifts together, means for supplying nails to the nailing means, and automatic means dependent upon the operation of said manually operable alining means for effecting the operation of said pressure-applying means, said nailing means, and said nail supplying means.

40. A heel alining and nailing machine having, in combination, means for receiving and alining a heel of loosely assembled lifts, and automatic means dependent upon the operation of said alining means for supplying nails and nailing together the alined lifts.

ERASTUS E. WINKLEY.
